JOURNAL LUBRICATOR

Llewellyn E. Hoyer, Wyckoff, and Edward R. Goreyca, Mahwah, N.J., assignors to American Brake Shoe Company, New York, N.Y., a corporation of Delaware
Filed Dec. 1, 1958, Ser. No. 777,381
5 Claims. (Cl. 308—88)

This invention relates to a lubricator for properly lubricating the journal of a railroad car rotatably supported within a journal box.

Historically, journals of the foregoing kind have been lubricated by oil-soaked waste packed in the bottom of the journal box below the journal, but it is now generally agreed that such is largely responsible for the creation of many hazards especially in view of the increasing speeds of railroad traffic.

The primary object of the present invention is to construct a lubricator for the journal of a railroad car which does not depend upon waste packing and to have as few parts as possible subject to failure in the construction. Specifically, it is an object of the present invention to construct a lubricator of this kind with a relatively large flexible base capable of conforming precisely to the contour of the inner surface of the journal box in the lower part thereof and having a pair of U-shaped holding arms projecting from the side thereof that is opposite the journal, these arms being removably mounted on the base and serving to hold a lubricating wick against the journal. If for some reason one of the arms should fail, such can be easily replaced, and the particular arrangement to be disclosed is one that accounts for the relay of copious amounts of oil to the journal.

Another object of the present invention is to enable such a lubricator to be retained in the journal box against shifting and to assure that the wick will only contact those parts of the journal which require lubrication.

Other and further objects of the present invention will be apparent from the following description and claims and are illustrated in the accompanying drawings which, by way of illustration, show preferred embodiments of the present invention and the principles thereof and what is now considered to be the best mode contemplated for applying these principles. Other embodiments of the invention embodying the same or equivalent principles may be used and structural changes may be made as desired by those skilled in the art without departing from the present invention and the purview of the appended claims.

In the drawings:

FIG. 1 is a top plan view of the base of the present lubricator;

FIG. 2 is an elevation of the base, partly in section;

FIG. 3 is a broken plan view of one of the lubricator arms;

FIG. 4 is a view taken substantially on the line 4—4 of FIG. 3;

FIGS. 4A, 4B and 4C show different modifications for realizing the separable connection between the lubricator arm and the base;

FIG. 5 is a partial transverse sectional view of a standard journal box showing the way in which the present lubricator is to be mounted therein; and

FIG. 6 is a partial longitudinal sectional view showing the installed state of the present lubricator.

The lubricator of the present invention illustrated includes a flexible base 11, FIG. 1, of resilient material such as hard rubber, plastic, molded fabric, foam or the like capable of being easily flexed to conform to the shape of the interior of the journal box JB of a railroad car illustrated in FIGS. 5 and 6. Of course the material

2

of which the base is composed as well as that of the arms to be described hereinafter should be of relatively durable and oil-resistant material. The base 11 is relatively thin in nature, and when positioned within the journal box has the lower face thereof in good frictional contact with the inside of the journal box. In respect of the transverse dimension of the journal box, FIG. 5, the base 11 has a width such that when mounted within the journal box the free ends E thereof will lie approximately below the waste retainer ledges WL that are conventionally provided in a standard railroad journal box. If these ribs are absent, the corresponding dimension of the base can be enlarged so as to lie close to the lower radius of the stop column, but it has been found that the extensive area of the base 11 establishes a great deal of friction and hence there is little tendency for the base to shift under actual operating conditions due to the motion of the journal. In any event, the waste retainer ledges or the stop columns where present account for stops that limit transverse shift of the base 11.

Further with regard to the dimensions of the base 11, and referring in particular to FIGS. 1 and 6, the base 11 has a predetermined front to rear dimension LD, and this dimension is approximately the dimension of the journal box between the front one of the two walls at the back of the box which afford the dust guard slot DS and the beginning of the upwardly directed contour at the front of the journal box, FIG. 6, where the closure lid (not shown) is ordinarily hingedly mounted. By so dimensioning the length of the base 11, assurance is had that there will be no significant shifting of the base 11 parallel to the axis of the journal J, and hence the arms and the wicking cover to be described hereinafter are accurately and permanently, so to speak, oriented relative to the car journal.

In order to assure proper seating and orienting of the base 11, the front and rear extreme edges of the base are notched or interrupted at 11N in a symmetrical fashion. This accounts for a plurality of spaced rear surfaces RS and a plurality of front surfaces FS which afford plural discontinuous lines of contact respectively at the rear of the base where it contacts the dust guard wall referred to above and at the front bottom of the journal box where the front wall is directed upwardly as mentioned above. It will thus be seen that the base in the present instance is so constructed as to assure a substantially fixed state thereof within the journal box as well as a non-canting orientation fully conformed to the shape of the bottom inside surface of the journal box as well as part way up the vertical sides thereof as best shown in FIG. 5. Additionally, spring means are provided which assure conformance of the base to the interior of the journal box and this is attained by embedding a plurality of strips 15 of spring steel or the like in the base 11 during molding thereof. The base 11 as it comes from the mold is generally flat and rectangular as illustrated in FIGS. 1 and 2, but incidental to installing the lubricator the base 11 is flexed as shown in FIG. 5.

Lubrication is accomplished in the present instance by a wick strip or cover 20 held firmly against the lower part of the journal by a pair of generally U-shaped arms 21 and 22 which are removably joined to the face or side of the base which is disposed toward the journal. The arms 21 and 22 are preferably molded from the same material as that of the base 11, and in the as-molded state these arms are generally flat and rectangular as shown in FIG. 3. To assure firm urging of the wick against the journal, each of the wick-holding elements 21 and 22 is associated with spring means or the like molded in an embedded state within the main body portion of the arms 21 and 22. The spring inserts thus described are oriented in a symmetrical fashion to assure uniform

pressures throughout the base and throughout the arms.

The front to rear dimension of the base was described above. The front to rear dimension of the arms 21 and 22 is shorter, and this dimension is indicated at SD in FIGS. 1, 3 and 6 and is substantially the same as the distance separating the collar C of the journal and the fillet surface FLS of the journal which is just forward of the dust guard seat DGS of the journal. The wick 20 also has the dimension SD, and in this way lubricant is relayed only to the essential part of the journal, namely, that which lies between the collar and the fillet surface FLS, and this dimensioning also assures that the wick cover will be prevented from being grabbed by the journal during rotation.

The flexible U-shaped arms 21 and 22 can be removably mounted on the upper face of the base in various different ways as will now be explained. Thus, referring to FIGS. 1, 2 and 5, the upper face of the base is provided with elongated dove-tail slots 30 which are afforded by pairs of correspondingly spaced and configured ribs 31 which project from the upper face of the base 11. The long edges of the arms 21 and 22 are molded so as to have a complementary dove tail as 21D and 22D. The spacing between the slots 30 in a lateral or transverse direction as viewed in FIGS. 1 and 2 is substantially less than the width of the arms 21 and 22 so that it is necessary to flex the latter in the manner shown in FIG. 5 to bring about registry of the dove tails with the related slots, whereupon the dove tails of the thus flexed arms are slipped into the receiving and retaining slots 30. This is selected as a relatively tight fit so as to maintain the parts assembled by friction.

Other forms of connection are illustrated in FIGS. 4A, 4B and 4C. Thus, in FIG. 4A, the base 11A representing the modified base is provided with raised ribs RA which are spaced to afford a rectangular slot therebetween. The end of the modified arm 21A is of uniform dimension to fit loosely in the slot between the ribs RA, and a pin-type fastener F is extended through and between the aligned areas of the ribs RA and the interposed portion of the free end of the cover supporting arm 21A to secure the latter removably to the base 11A.

As illustrated in FIG. 4B, the lubricator base 11B has a dove tail slot extended all the way through, that is, this dove tail slot opens at both the upper and lower faces of the base 11B. This dove tail slot has a length which corresponds to that of the ribs 31, FIG. 1, and the dove tail end of the cover supporting arm 21B, FIG. 4B, is manipulated so as to enable the latter to fit complementarily in the dove tail slot in the base 11B.

Referring to FIG. 4C, one fastening end of the modified arm 21C is provided with a T-head 21T, which underlies the bottom of the modified base 11C. The intermediate portion of the arm 21C extends upwardly through a rectangular slot in the base 11C, and the opposite fastening end of the arm 21C can be of the modified form shown in FIG. 4A.

In any event, after the arms have been flexed and removably secured in place, the cover 20 is then draped over the convex upper sides of the arms 21 and 22, and the cover is secured in place by removable fasteners F, FIG. 5, of any desired kind. Preferably, the cover 20 is of one piece with the intermediate or medial portion 20M thereof hanging loosely in the area above the base that lies between the adjacent inner ends of the arms 21 and 22. By so hanging loosely, the medial portion of the wick or cover will be submerged in the greatest depth of oil at the bottom of the journal box when the lubricator is located within the latter. It will be recognized of course that the arms 21 and 22 are so dimensioned with respect to the spacing between the base 11 of the lubricator and the lower half of the journal J as to be slightly bowed in a concave fashion when properly positioned as illustrated in FIG. 5, and this coupled with the return tension of the spring inserts 25 presses

the wick firmly against the lower two quarters of the journal.

It will be recognized that the base 11 is fully symmetrical so far as front and rear positions are concerned, and hence it is immaterial which side is first located within the journal box. Advantageously, symmetrically located openings 40 and 41 are provided at medial areas of the front and rear margins of the base 11. These openings are adapted to receive a hook tool for extracting the lubricant from or adjusting the same within the journal box, and if desired the openings 40 and 41 can be reinforced.

It will be seen from the foregoing that in accordance with the present invention there is afforded a journal lubricator of relatively simple construction but one which fulfills the essential role of feeding copious amounts of oil to the journal from the bottom of the journal box. The construction includes a flexible base of generous area having good frictional contact with the inside of the journal box tending to resist shifting movement in the first instance, but the base is dimensioned to take advantage of the journal box construction in limiting shifting movement as has been explained. The arms 21 and 22 are of unique construction and are adapted to firmly hold the oil drenched wick against the journal. In the event that the wick becomes worn, the wick can easily be replaced, without any effect on remaining parts of the lubricator, and in the event that the arms become worn, these too can be easily replaced.

Hence, while we have illustrated and described preferred embodiments of our invention it is to be understood that these are capable of variation and modification, and we therefore do not wish to be limited to the precise details set forth, but desire to avail ourselves of such changes and alterations as fall within the purview of the following claims.

We claim:

1. A lubricator for a journal disposed for rotation within a journal box and comprising, a base member in the form of a generally flat and rectangular sheet of flexible resilient hard rubber material having spaced-apart undercut slots formed therein, a pair of separate U-shaped one-piece arms composed of said material and each having ends formed complementary to said slots and removably mounted therein, wicking material secured to the convex sides of said arms opposite the base and including a portion disposed closely adjacent the medial part of said base member between said arms, and spring means embedded in said base and said arms.

2. A lubricator for a journal disposed for rotation within a journal box and comprising, a base member in the form of a generally flat and rectangular sheet of flexible resilient material, a pair of U-shaped arms composed of said material, said base member having spaced apart connecting means formed therein and each of said arms having opposite ends removably fastened to said connecting means in said base, spring means embedded in said arms for urging said arms away from said face of said base, and wicking material having portions secured to the faces of said arms which are opposite said face of said base including a portion disposed closely adjacent said base member between said arms.

3. A lubricator according to claim 2 wherein the base has a predetermined length and wherein said arms are of shorter length.

4. A journal lubricator of the kind described disposed within the journal box of a railroad car between the bottom of the box and the bottom of the journal and comprising a base of flexible material having a lower face in complementary contact with the bottom of the box and part way up the sides, said base being continuous between the dust guard slot and the upwardly directed portion of the journal box at the front and having symmetrically arranged notches formed in the front and rear edges thereof, a pair of U-shaped arms of resilient material having

ends separately attached to the upper face of the base and each being continuous from approximately the collar journal to the journal fillet surface just forward of the dust guard seat of the journal, spring means embedded in said arms, and wick means on said arms urged into contact with the lower part of the journal and dipping into oil in the bottom of the journal box.

5. A lubricator as defined in claim 1 wherein said base member includes raised ribs defining said undercut slots.
